UNITED STATES PATENT OFFICE.

WILLIAM M. DUNCAN, OF ALTON, ILLINOIS.

FURNACE.

1,324,884.

Specification of Letters Patent. Patented Dec. 16, 1919.

Application filed December 6, 1915, Serial No. 65,247. Renewed May 8, 1919. Serial No. 295,700.

To all whom it may concern:

Be it known that I, WILLIAM M. DUNCAN, a citizen of the United States of America, residing at Alton, in the county of Madison, 5 State of Illinois, have invented certain new and useful Improvements in Furnaces, of which the following is a full, clear, and exact description, reference being had to the accompanying drawings, forming a part of 10 this specification.

My invention relates to a furnace equipped with a mechanical stoker and other elements adapted to be associated therewith to provide for the combustion of 15 anthracite coal on a traveling grate. Under some conditions, where anthracite coal is the most desirable fuel, and in some localities where such coal is not too expensive, there is a marked demand for mechanical 20 stokers capable of handling anthracite coal, and attempts have, therefore, been made to burn coal of this kind on traveling chain grates. However, the various conditions essential to the ignition and combustion of 25 anthracite coal are quite different from the conditions necessary in burning bituminous coal, and the desired new conditions cannot be obtained in the ordinary mechanical stokers.

30 The preferred form of the present invention comprises means for supplying anthracite coal to a traveling grate at two different points, the grate being adapted to carry coal from one of said points to the other. The 35 object in supplying coal at two points, instead of delivering all of the coal to the grate at one point, is to facilitate the ignition and combustion of the coal. The new structure preferably includes two coal re-

40 ceptacles, from which the coal is discharged onto the grate at two different points, and, for the sake of convenience in describing the invention, I will term one of these receptacles "a primary coal receptacle" and the 45 other "a secondary coal receptacle". The comparatively thin bed of anthracite coal passing from the primary receptacle will ignite and burn more readily than a larger body of anthracite coal, and the parts of the 50 new apparatus are so constructed and arranged that this comparatively thin bed of coal will be fully ignited before it reaches the point at which the green coal is discharged from the secondary coal receptacle.

55 The body of coal traveling from one of the

discharge points to the other is preferably subjected to the action of an induced draft, whereby flame and hot gases in the fire-box are drawn toward this comparatively thin body of coal, thus providing 60 for the ignition and combustion of the coal near the primary discharge point. Before this body of coal reaches the secondary discharge point, it is preferably subjected to the action of a forced draft so that the green 65 coal dropping onto the burning coal will be readily ignited at or near the secondary discharge point.

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I is a longitudinal section of a furnace, embodying the features of my invention.

Fig. II is a top or plan view illustrating the endless fuel carriers and the draft appliance associated therewith, some of the 85 elements of the draft appliance being shown diagrammatically.

Fig. III is an enlarged vertical section taken approximately on the line III—III, 90 Fig. I.

Fig. IV is an enlarged detail view showing a portion of the bottom wall of one of the draft-boxes and the closures fitted to said bottom wall.

Fig. V is a section on line V—V, Fig. IV. 95 1 designates the side walls of a furnace, and 2 designates tracks located between said side walls. Side frames 3 and 4 are provided with wheels which rest upon the tracks 2. A drive shaft 5, mounted in the side 100 frames at the front of the grate, is provided with a series of sprocket wheels 6 which lie between the side frames 3 and 4. An idle shaft 7 at the rear of the grate is provided with idle wheels 8. The wheels 6 and 8 constitute supporting elements for a series of traveling fuel carriers, and each of these fuel carriers comprises an endless sprocket chain 9 fitted to one of the sprocket wheels 6 at the front of the grate and also fitted to 110

an idle wheel 8 at the rear of the grate. Each fuel supporting unit is a rectangular plate 10 having perforations for the admission of air to the fuel, and provided with 5 legs which are secured to the pivot pins forming part of the endless chain structure. The fuel supporting members 10 lap each other, as shown in Figs. I and III.

The draft appliance comprises manifolds 10, 12, 13, 14 and 15, arranged transversely of the chain grate structure, and secured at their ends to the side frames 3 and 4. Pressure pipes 16, passing through a furnace wall 1, are fitted to the manifolds 13, 14 and 15 and provided with valves 17 for regulating the flow of air through the manifolds. Each valve 17 is adapted to control the draft in only one of the manifolds, and these valves may be adjusted independently 20 of each other to vary the draft at different parts of the fuel bed. A suction pipe 18, is fitted to the manifold 12, as shown in Figs. II and III. The suction pipe 18 leads to the intake opening of a blower, or blast 25 device 19, the latter being shown diagrammatically in Fig. II. A discharge pipe 20, leading from the blower 19, is connected to the pressure pipes 16. 21 designates a valve for controlling the flow of gases through 30 the suction pipe 18. From the foregoing it is to be understood that the draft appliance is adapted to create an induced draft in the manifold 12 and a forced draft in the manifolds 13, 14 and 15.

35 The draft boxes for conducting gases to and from the fuel bed, are arranged longitudinally of the grate, each manifold being in communication with a series of draft boxes. The manifold 12, near the front of 40 the grate, communicates with draft boxes 22 and 22'; the boxes 22' being located at the sides of the grate, as shown in Figs. II and III, and the draft boxes 22 being located between said draft boxes 22'. Each 45 draft box is closed at its sides and ends, and open at the top to permit the gases to circulate through the perforations in the fuel supporting members 10. The different draft boxes are separated from each other to provide 50 passageways for the endless sprocket chains 9, which travel between said draft boxes.

Draft boxes 23 and 23', located adjacent to the draft boxes 22 and 22', are provided 55 with end walls 24 and bottom and side walls connecting said end walls. All of these draft boxes 23 and 23' are in communication with the manifold 13, and they are separated from each other to permit the sprocket 60 chains to pass between them. Draft boxes 25 and 25' are open at the top and provided with side, end and bottom walls, said draft boxes being in communication with the manifold 14. 26 and 26' designate rear 65 draft boxes abutting against the draft boxes

25 and 25', respectively, said rear draft boxes being in communication with the manifold 15.

The draft boxes are connected together to form several longitudinal rows of boxes, 70 but the draft boxes 22 and 22' near the front of the grate, are not in communication with any of the other draft boxes. In other words, each series of draft boxes is arranged transversely of the grate so as to 75 communicate with only one of the manifolds 12, 13, 14 or 15. When the blower 19 is in operation, an induced draft is created in the draft boxes 22 and 22', a forced draft being created in the other draft boxes. Hot 80 gases generated in the fire-box are drawn downwardly through the grate at a point above the draft boxes 22 and 22'. These gases flow through the manifold 12, suction pipe 18, blower 19, discharge pipe 20, pressure pipes 16, into the manifolds 13, 14 and 15, through the draft boxes 23, 25 and 26 85 and then to the fuel which lies immediately above the last mentioned draft boxes. The combustible gases circulating from the fire-box in response to the action of the induced draft, are returned in response to the action of the forced draft. 90

30 designates tracks arranged in the upper portions of the draft boxes to receive the 95 lapped marginal portions of the fuel supporting members 10. Guide-members 31, extending forwardly from the front ends of the draft boxes 22, are adapted to guide the fuel supporting members onto the draft 100 boxes.

Discharge openings 32 are formed in the bottom of each draft box, said discharge openings being normally closed by doors or closures 33. The closures 33 in each longitudinal row of draft boxes are secured together by a connecting bar 34, so that all of the closures may be operated at the same time. The means for operating the closures comprises a rock shaft 35 having a series of 105 arms 36, the upper ends of said arms being secured to the closures 33 near the front of the grate. The means for actuating the rock shaft 35 comprises an arm 37 secured to one end of said rock shaft, and an operating rod 38 connected to said arm. When the grate is in service, ash, etc. will drop through the perforations in the fuel supporting members and fall onto the bottom walls of the draft boxes 23, 25 and 26. Such 110 material may be readily blown through the discharge openings 32 by opening all of the closures 33 when air under pressure is flowing through the manifolds 13, 14 and 15. 115

In the preferred form of the invention, 120 a primary coal receptacle 40 (Fig. I) is located above the grate at a point near the front of the furnace. This coal receptacle is open at the bottom to permit the 125 discharge of coal onto the grate, and when the 130

grate is in service the coal travels from said receptacle toward the rear of the furnace, as indicated by arrows in Fig. I. A secondary coal receptacle 41, located above the 5 grate, is provided with a discharge opening 42 through which coal may be discharged as indicated by arrows in Fig. I. 43 designates a rotary feeder arranged in the bottom of the secondary coal receptacle 10 41, and provided with a sprocket wheel 44 which lies at the exterior of said coal receptacle. A drive chain 45, passing around the sprocket wheel 44, is fitted to a drive wheel 46, the latter being secured to the 15 drive shaft 5. 47 designates an adjustable gate located near the bottom of the coal receptacle 41 to control the flow of coal to the feeder 43.

It is important to note that the coal is 20 discharged onto the traveling grate at two different points, the path of the coal being indicated by the arrows shown by full lines in Fig. I, and the directions of the draft being indicated by dotted lines. The induced draft boxes 22 are located near the discharge end of the primary coal receptacle 40, so that the flame and hot gases will be drawn onto the coal at a point adjacent to said primary coal receptacle, the object being 25 to ignite this comparatively thin body of coal before it reaches the point at which the coal is delivered from the secondary coal receptacle. The hot gases flowing to the draft boxes 22, are drawn in a direction 30 opposed to the direction in which the fuel travels. An ignition arch, consisting of a series of heat radiating blocks 50, is preferably located above the grate in a plane between the two points at which coal is delivered 35 to the grate.

When the coal passing from the primary coal receptacle 40 reaches the plane of the draft boxes 23, it is subjected to the action of the forced draft flowing from said draft boxes, and thereafter the coal passing from the secondary receptacle 41 is discharged 45 onto the burning coal when the latter is subjected to the action of the forced draft.

The green coal discharged at the last mentioned point will readily ignite as it travels with the burning coal, the draft being upwardly so as to insure the desired ignition and combustion.

The combination of draft boxes and fuel 55 carriers, arranged as herein disclosed, is claimed in an application for patent filed by me November 20, 1915, Serial No. 62,507, furnaces, renewed May 8, 1919, Serial No. 295,699.

60 I claim:—

1. In a furnace, the combination with a fire-box provided with a traveling grate, of draft producing means providing for an

up-draft through the grate at one point, then in a direction contrary to the direction 65 of movement of the grate, and then downwardly through the grate.

2. In a furnace, a fire-box provided with a traveling grate, means for supplying fuel to said grate, and means for creating an induced draft in said fire-box in a direction 70 contrary to the direction of movement of said grate and then downwardly through the fuel on the grate.

3. In a furnace, the combination with a 75 fire-box provided with a traveling grate, of draft producing means providing for a continuous up-draft through the grate at one point, then in a direction contrary to the direction of movement of the grate, then 80 downwardly through the grate, and then back to the point at which the draft first passes through the grate.

4. In a furnace, a fire-box provided with 85 a traveling grate, means for supplying fuel to said grate at two different points, one in advance of the other relative to the direction of movement of the grate, and a draft appliance for creating an induced draft in said fire-box in a direction contrary to the 90 direction of movement of said grate and then downwardly through the fuel on the grate between the two points at which the coal is delivered to the grate.

5. In a furnace, a fire-box provided with 95 a traveling grate, means for supplying coal to said grate at two different points, one in advance of the other relative to the direction of movement of said grate, and means for creating a forced draft through one portion of said grate and an induced draft through another portion of said grate, said draft producing means providing for the induced draft passing downwardly through the fuel on the grate between the two points 105 at which fuel is delivered to the grate.

6. In a furnace, a fire-box provided with a traveling grate, means for supplying fuel to said grate at two different points, one in advance of the other relative to the direction of movement of said grate, and a draft producing means for creating a forced up-draft through the grate adjacent the advance fuel supply point and an induced down-draft 110 through the portion of the grate between 115 the two points of supply of fuel to the grate.

7. In a furnace, a fire-box provided with a traveling grate, means for supplying fuel to said grate at two different points, one in advance of the other relative to the direction of movement of the grate, and means for creating both an induced down draft and a forced up-draft through said grate between the points at which the fuel is delivered thereto.

WILLIAM M. DUNCAN.
